UNITED STATES PATENT OFFICE.

JULES HECTOR HIRT, OF EL PASO, TEXAS.

SODA-ASH PROCESS.

1,141,639.

Specification of Letters Patent.

Patented June 1, 1915.

No Drawing.

Application filed February 11, 1913. Serial No. 747,606.

To all whom it may concern:

Be it known that I, JULES HECTOR HIRT, a citizen of the United States, residing at El Paso, in the county of El Paso and State of Texas, have invented certain new and useful Improvements in Soda-Ash Processes, of which the following is a specification.

This invention relates to a soda-ash process and product and its object is to produce 10 soda ash (Na_2CO_3) at low cost.

In carrying out my new process, I take approximately anhydrous sodium-sulfate (Na_2SO_4) and mix it with about one-half its weight of saw-dust, either wet or dry, 15 and charge the hot end (near the fire bridge) of a reverberatory tank-furnace, preferably continuously, with the mixture. Under the furnace heat, the sodium sulfate melts at a temperature of $889^\circ C.$ and immediately begins to be reduced by destructive distillation 20 of the saw-dust, to sodium sulfid, in consequence of the combined action of volatile, heavy hydrocarbons in the saw-dust and of the extremely porous charcoal into which 25 the saw-dust is converted by the destructive distillation of it.

The sodium sulfid produced, fuses at a temperature of about $600^\circ C.$, and in consequence the bath of sodium sulfid is extremely 30 mobile, having a consistency about that of milk. In this freely fluid state it can be readily tapped from the furnace tank. This freely-flowing sodium-sulfid product of the furnace is partially protected from oxidation 35 in air by the soot which is disseminated through the bath, the soot resulting from the destructive distillation of the saw-dust. And while in the furnace, the saw-dust floats on top of the sodium-sulfid bath and 40 there protects the bath from oxidizing action by the flame.

An advantage of using the saw-dust is that the hydrocarbons released in the destructive distillation of the saw-dust effect 45 a very rapid reduction of the sodium sulfate to sodium sulfid and produce most of the soot which protects the molten sulfid from oxidation. The importance of protecting the molten sulfid from oxidation is that if it 50 be not so protected when tapped out in its liquid form from the furnace, it will burst spontaneously into flame and thereby will revert, or will tend to revert, back into sodium sulfate.

55 The saw-dust floating on the bath consti-

tutes a covering of more or less depth, and which is exposed directly to the reverberatory-furnace flame and heat. The temperature of the bath is necessarily higher than the temperature of the saw-dust, and the bath boils up through the saw-dust covering while the saw-dust is undergoing the destructive distillation, so that the oxidation-resistant soot is well distributed throughout the molten sulfid. As saw-dust contains only about one-third of one per cent. of ash, its use results in a purer product than would be obtained if coal or coke, which contains about ten per cent. of ash, were used in lieu of the saw-dust.

The sodium sulfid may be used immediately and continuously in the production of soda ash.

In making soda ash (Na_2CO_3) the freely fluid sodium sulfid is tapped from the furnace directly, while at the temperature of its molten state into wet saw-dust in which its temperature is so reduced that it solidifies in small pieces, or a granulated state. This granulated sodium sulfid, with its associated wet saw-dust, is then mixed with raw limestone ($CaCO_3$) in about the proportion, preferably, of three parts of limestone to one part of sodium sulfid, with one-fourth part of saw-dust present; and the mixture is then charged into a vertical externally-heated kiln from the bottom of which crude soda ash is withdrawn for subsequent purification in a known manner.

The raw limestone, being about 100 per cent. in excess of the actual quantity required to effect the requisite chemical reaction for obtaining the soda ash, operates to prevent the kiln charge from sticking to furnace parts in large hot masses, as in the Leblanc process, and consequently diminishes much of the expensive procedure of that process. The carbonating of the sodium sulfid into sodium carbonate involves an exothermic chemical reaction, and consequently proceeds with rapidity at about a red heat, which is of substantial economical importance. This exothermic reaction is indicated by the following formula expressed in molecular calory units:

an excess of 4850 calory units.

Any suitable ingredient may be used in lieu of the saw-dust.

What I claim is:

1. The process of making soda ash consisting in making sodium sulfid in hot, fluid state; granulating it in wet saw-dust; mixing it and wet saw-dust with raw limestone in excess and in subjecting the mixture of granulated sodium sulfid, wet saw-dust, and raw limestone to heat which effects reaction of the constituents of said mixture rapidly and at about red heat. 20
2. The process of making soda ash, consisting in subjecting a mixture of sodium sulfid, wet saw-dust, and raw limestone to heat sufficient to effect reaction of the constituents rapidly at about red heat. 25
3. The process of making soda ash, con-

sisting in flowing hot sodium sulfid into mixture with moist saw-dust and raw limestone in excess, and in heating the mixture to about red heat to effect chemical reaction.

4. In the process of making soda ash, the step consisting in flowing hot sodium sulfid into moist saw-dust to reduce the temperature of the sulfid below its spontaneous ignition point.

In testimony whereof I affix my signature in presence of two witnesses.

JULES HECTOR HIRT.
